UNITED STATES PATENT OFFICE

JOSEPH BEHLE, OF DALLAS, TEXAS, ASSIGNOR TO THE MURRAY COMPANY, OF DALLAS, TEXAS, A CORPORATION OF TEXAS

PRESS DOOR CLAMPING DEVICE

Application filed August 24, 1929. Serial No. 388,216.

This invention relates to new and useful improvements in cotton press door mechanism.

One object of the invention is to provide means for actuating the operating shafts of door fastening elements such as are shown in the Letters Patent No. 1,706,663, issued to W. L. Hancock, March 26, 1929.

Another object of the invention is to provide improved means for simultaneously revolving a pair of shafts in opposite directions by a common operating member.

A further object of the invention is to provide operating means for press door fastening devices arranged operative positively and in unison and free from slippage.

A construction designed to carry out the invention will be hereinafter described together with other features of the invention.

The invention will be more readily understood from a reading of the following specifications and by reference to the accompanying drawings in which an example of the invention is shown, and where

Figure 1 is a side elevation of the upper position of a press equipped with operating means constructed in accordance with the invention.

Figure 2 is an end elevation of the same.

Figure 3 is a sectional view of one of the gear units.

Figure 4 is a sectional view of the other gear unit.

Fig. 5 is a detail of one of the door fastening devices, and

Fig. 6 is a perspective view showing a modified form of operating means.

In the drawings the numeral 10 designates a press box, 11 one of the frame standards, 12 a pair of channel beams secured to the sides of the standard and supporting the top platen members 13, all of which may be of any approved construction.

On each channel beam 12 is mounted a plurality of hanger brackets 14 having bearing boxes 15 at their outer ends in which shafts 16 are journaled. The shaft on each side of the press box overhangs a correlated side door 17. A plurality of eccentrics 18 are fastened on each shaft, three being shown, but the

number may vary. It is preferable to mount the eccentrics adjacent the boxes 15, as is obvious.

Clamp arms 19 are hung from the eccentrics, each arm having a ring 20 at its upper end surrounding one of the eccentrics, so that upon a rotation of the eccentrics by the shaft, said arms will be raised and lowered. The arms have shoes 21 at their lower ends and the shoes on one side of the platen are connected with the shoes on the opposite side of bridle rods 22 extending through vertical slots 23 in the platen bars.

Each rod 22 has its ends penetrating the shoes and is screw threaded to receive nuts 24. Coiled springs 25 (Fig. 5) are confined on the rods between the shoes and the ends of the platen bars. Each shoe has a cam face 26 for engaging the upper edge of the door 17 when the arms 19 are lowered, thus fastening said doors. All of the elements which have been recited are shown in the aforesaid Hancock patent and form no part of the present invention.

In carrying out the invention a transverse metal plate 27 is fastened on the outer side of the standard 11 and the shafts 16 penetrate this plate. A pair of gear housings 28 are fastened on the outer side of the plate and have bearing collars 29 receiving the ends of said shafts.

On each shaft within its respective housing is fastened a worm gear 30. Each has a depending worm box 31 having bearing collars 32 at its ends. A transverse operating or worm shaft 33 extends through one of the boxes and terminates in the box. On its exposed end the worm shaft has a hand wheel 34 for manually rotating it.

In one of the boxes 31 a right hand worm screw 35 is fastened on the shaft 33 while in the other box a left hand worm screw 36 is secured on said shaft. By this arrangement the gears 30 are revolved in opposite directions when the worm shaft is rotated. Thus upon turning the hand wheel 34 in one direction the shafts 16 are rotated to lower the clamping arms and upon turning it in the opposite direction the arms are raised.

Each gear housing and its contents con-

stitutes a gear unit. The worm gear operating means is positive and sturdy and permits the arms to be forced down over the edges of the doors, easily and readily. This 5 means also assures a unified operation and precludes stoppage of the operating parts. Further no fastening means is required to hold the arms 19 elevated.

In Fig. 6 the plate 27 is omitted and the 10 gear housings 28 are permitted to float on the shafts 16. This form has given satisfaction, but by use of the plate a more steady device is provided.

Various changes in the size and shape of 15 the different parts, as well as modifications and alterations, may be made within the scope of the appended claim.

What I claim is:

In a press door fastener operating device, 20 the combination with the frame of a press, of door fastener operating shafts mounted horizontally on each side of the top of the frame, worm gears, one on one end of each shaft, a horizontal actuating shaft extending 25 from one operating shaft to the other shaft, worms on the actuating shaft meshing with the gears, gear housings surrounding the gears and the worms and in which the actuating shaft is journaled and supported, and 30 a hand wheel mounted on the actuating shaft, the housings being mounted directly on the operating shafts.

In testimony whereof I affix my signature.

JOSEPH BEHLE.
